UNITED STATES PATENT OFFICE

DANIEL BAKER DIMICK, OF BIRMINGHAM, ALABAMA

PATTERN LIFTING DEVICE

Original application filed October 23, 1929, Serial No. 401,767. Divided and this application filed December 26, 1930. Serial No. 504,971.

The present invention relates to improvements in pattern lifting devices, and is a division of my copending application Ser. No. 401,767, filed October 23, 1929, entitled

5 Method and apparatus for casting pipe.

An object of the invention is to provide an improved pattern lifting device, whereby the pattern may be lifted from the mold flask effectively and conveniently, and in which

10 great force is exerted to break the static friction existing between the pattern and the sand.

Another object of the invention lies in providing an improved pattern lifting device, in which the parts of my improved mold flask are availed of to cooperate with a novel form of lifting means, whereby initially greatly increased pressure is brought to bear upon the pattern to start the same out of

20 the sand.

With the foregoing and other objects in view, the invention will be more fully described hereinafter and will be more particularly pointed out in the claims appended

25 hereto.

In the drawing, which shows only one embodiment of the invention,

The figure is a fragmentary vertical section of a mold flask, with the improved

30 lifting device applied to the pattern preparatory to raising the same.

Referring more particularly to the drawing, 24 designates the cheek or outside retaining wall of the flask, and 26 represents

35 the inner core arbor; between which parts the sand is rammed. The core arbor 26 may

be provided with wings 28 to support and

hold the molding sand in place in the core of

the finished mold.

40 The pattern is shown at 29. This pattern is constructed for the straight bore of the desired pipe and also for the outside of the bell of said pipe. The top portion of the pattern 29 is extended to receive means for

45 withdrawing the pattern from the flask mold,

and for this purpose, openings 30 are pro-

vided in the upper extended portion of the

pattern. The outside stripping plate 37 is

machined in bore to the outside diameter of

50 the top or enlarged bell end of the pattern

29. The inside stripping plate 38 is machined on its outer diameter to the bore of the pattern. A weighted or massive cast iron centering plug 39 rests upon the arbor 26 and within the inner stripping ring or plate 38. The engaging surfaces of the plug 39 and stripping plate 38 are properly machined and the outside surface of the plug 39 is preferably tapered as shown. The outside stripping plate 37 is held in place by the use of clamps 40 in a well-known manner. The tempered molding sand rammed in place between the pattern 29 and cheek 24 is represented at 41, and the sand between the pattern 29 and the arbor 26 is shown at 42.

55 Referring to the lifting device for the pattern, 70 designates the hook ring, being part of the pattern drawing mechanism, while 71 designates the pattern hooks which are carried by the chains 72 and 73. Hold-down lugs 74 are welded or otherwise secured to the pattern hooks 71.

60 A wooden or metal bridge 75 is provided with legs 76 which rest on the inside stripping plate 38. The bridge is adapted to receive vertical pressure from the lugs 74, as

hereinafter described.

65 In operation, the hook ring 70 is adapted to receive a power lifting crane hook. The wooden bridge 75 is placed with its two legs 76 resting on the inside stripping plate 38. The hooks 71 are engaged in the openings in the upper end of the pattern 29, and the lugs 74 rest upon the bridge 75. Lifting action by

70 the crane acting on ring 70 exerts an angular

upward pull on the grab hooks 71. The lifting

strain is exerted on straight lines through

the chains 72 and 73, but because of the form

of the triangular or wedge lugs 74, the grab

75 hooks 71 will be prevented from taking a po-

position in alignment with the lengths of the

chains 72 and 73. The lifting strain there-

by exerts an inward circular force on the

70 grab hooks 71 around the center of the lower

circular hook part as an axis. This circular

85 force is resisted by the downward pressure

of the lugs 74 against the bridge 75.

80 With this appliance, the core and inside

stripping plates 38 are held down, while the

85 pattern is withdrawn a sufficient distance to

break the static friction between the bore of the pattern and the sand of the core. By the time the pattern is lifted a sufficient distance to enable the lugs 74 to clear the bridge 75, the friction between the pattern bore and the core is so reduced that there is no possibility of this friction being enough to lift the core against gravity with the pattern as it is further withdrawn.

10 After the pattern 29 is completely removed from the mold, the stripping plates 37 and 38 are likewise removed. The centering plug 39 is, however, left in place. Subsequently, the completed flask mold is removed from 15 the molding machine and placed on the pouring floor.

It will be obvious that various changes in the construction, combination and arrangement of parts could be made, which could be 20 used without departing from the spirit of my invention, and I do not mean to limit the invention to such details, except as particularly pointed out in the claims.

Having thus described my invention, what 25 I claim and desire to secure by Letters Patent of the United States is:—

1. A lifting mechanism for drawing patterns from mold flasks comprising grab hooks for engaging the pattern having lugs, a 30 bridge piece fitted in the flask upon the inner stripping plate and engaged by said lugs, and means connected to the hooks for lifting the pattern and tending to rotate the hooks whereby to press the lugs firmly against the 35 bridge.

2. A lifting mechanism for drawing patterns from flasks comprising grab hooks adapted to engage with the pattern and having lugs thereon, a bridge piece having legs 40 for engaging the inner stripping plate of the flask and engaged by said lugs, chains coupled to said grab hooks, and a ring connected to said chains and adapted to be engaged by a hoisting mechanism.

45 3. A lifting mechanism for drawing patterns from mold flasks comprising means for engaging and lifting the pattern, and means acted on by a portion of the first named means whereby to hold the flask and the inner stripping plate thereof while the static friction incident to the raising of the pattern is broken.

4. A lifting mechanism for drawing patterns for mold flasks comprising hooks for 55 engaging the pattern, a bridge engaging the inner stripping plate of the mold, and means between said hooks and bridge for holding down the stripping plate during the initial 60 movement of the pattern.

5. A lifting mechanism for drawing patterns from mold flasks, comprising catch devices for engaging the pattern, lugs on said catch device, and means engaged by said lugs 65 and engaging the inner stripping plate for

holding the latter down during the initial movement of the pattern.

6. A lifting mechanism for drawing patterns from mold flasks, comprising catch devices for engaging the pattern, and means engaged by said catch devices and engaging the inner stripping plate of the mold to hold the latter down while the pattern is being initially lifted by said catch devices.

7. A lifting device for drawing patterns from mold flasks, comprising a ring device for engagement by a crane hook, chains extending from said ring device, grab hooks on said chains for engaging the pattern, a bridge engaging the inner stripping ring of the mold, and lugs on said hooks initially engaging the bridge to force the chains out of line and for transmitting the initial lifting strains to clamp down the bridge upon the inner stripping plate.

DANIEL BAKER DIMICK.
